US00D535651S

(12) **United States Design Patent** (10) Patent No.: **US D535,651 S**
(45) Date of Patent: **** Jan. 23, 2007**

(54) **WIRELESS NETWORK DEVICE**

(75) Inventors: **Shih-Chi Wong**, Tu-Cheng (TW);
Nai-Yo Chi, TuCheng (TW)

(73) Assignee: **Hon Hai Precision Industry Co. Ltd.**,
Taipei Hsien (TW)

(**) Term: **14 Years**

(21) Appl. No.: **29/252,258**

(22) Filed: **Jan. 20, 2006**

(30) **Foreign Application Priority Data**

Dec. 30, 2005 (CN) 2005 3 0158915

(51) **LOC (8) Cl.** **14-02**

(52) **U.S. Cl.** **D14/240**; D14/357

(58) **Field of Classification Search** D14/242,
D14/496, 125, 135-6, 167, 300-2, 314, 341,
D14/355-8, 362-70, 383, 385, 433, 348,
D14/353, 156; 379/413.04; 220/4.01-4.02;
361/679, 685-6; D13/103

See application file for complete search history.

(57) **CLAIM**

The ornamental design for a wireless network device, as shown and described.

DESCRIPTION

FIG. 1 is an isometric view of a wireless network device of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
